COMBINED SOLE AND HEEL UNIT FOR FOOTWEAR

Henry Bettle, Stocks Wicks Lane, Formby,
Lancashire, England

Filed June 3, 1966, Ser. No. 2,556

Claims priority, application Great Britain Feb. 24, 1966

Term of patent 14 years

(Cl. D2—320)

FIG. 1.

FIG. 1 is a bottom plan view of a combined sole and heel unit for footwear showing my new design;

FIG. 2 is a side elevational view thereof;

FIG. 3 is a rear elevational view; and

FIG. 4 is a top plan view.

I claim:

The ornamental design for a combined sole and heel unit for footwear, as shown.
